UNITED STATES PATENT OFFICE.

JAMES H. RAND, JR., OF TONAWANDA, NEW YORK.

CARD-INDEX DEVICE.

Application filed December 6, 1922. Serial No. 605,325.

This invention relates to card index or record devices and more particularly to card, label, or index slip holding and displaying members.

Heretofore card pockets or holders have been provided having at one edge a sheath of celluloid or other suitable transparent material. Index or record cards have also been provided with similar sheaths adapted to receive slips, labels or the like. Large quantities of celluloid are used in the manufacture of these articles and celluloid constitutes one of the most costly items of expense in the production of these cards or holders. In these devices, the celluloid sheath forms a pocket on one or more faces of the card and into which cards or slips may be inserted, and in order to secure these sheaths on the cards or holders it has been customary to fasten the sheaths to the paper or other material of which the card is made by means of wires, wire staples and the like. In cards or holders having a pocket at one side of the card, in order to effect a firm securing of the sheath to the card or holder, the rear side of the celluloid sheath is stapled to the card or holder at a point approximately centrally of its length. This has necessitated making the rear sides of the sheaths of greater width than the front portions thereof so that the rear side of the sheath may be stapled to the card or holder above the free edge of the sheath forming the pocket at the front of the card. In these constructions the rear side of the sheath which must be considerably wider than the front or pocket forming portion of the sheath, serves no function other than to assist in securing the sheath on the card or holder and contains a much greater quantity of celluloid than the pocket-forming portion of the sheath at the front of the card holder. The staples positioned centrally of the card or holder, by rubbing against adjacent cards or the sheaths of adjacent cards or holders when the devices are in use, tends to mar or damage those members.

The objects of the present invention are to provide a card index member having a card or label receiving and displaying sheath which is relatively inexpensive to produce; also to provide a card or card-holder having a card or label receiving and displaying sheath having improved means for securing the sheath to the card or holder; also to provide a card or card-holder having a

sheath for receiving and displaying a card or label in which a securing means for fastening the sheath on the card or holder operates to retain the card or slip in position in the sheath; also to provide improvements in devices of this kind in the other respects hereinafter set forth and claimed.

In the accompanying drawings:

Fig. 1 is a face view of a card index member provided with an improved sheath constructed in accordance with this invention, with a card in place therein.

Fig. 2 is a fragmentary rear view thereof on an enlarged scale.

Fig. 3 is an enlarged fragmentary transverse section on line 3—3, Fig. 1.

Fig. 4 is a fragmentary perspective view showing the improved means for securing the sheath to a card or card holder.

In the drawings, 10 designates a card or card holder of any usual or desired form. The sheath, which is preferably made of celluloid or other suitable transparent material, is provided with the pocket-forming portion 11 adapted to receive a label, slip or the like, or the edge of a card 12 supported on the member 10. In this device the amount of celluloid or other sheath-forming material is reduced to a minimum and the rear side of the sheath-forming material 13, instead of extending on the card or holder to a position beyond the free edge of the pocket-forming portion 11 of the sheath, extends only so far as is necessary to effect proper attachment to the member 10. The sheath is provided with opposite parts or portions gripping a portion of the member 10. These parts or portions are preferably integral with the sheath. For this purpose in the embodiment illustrated, the portion 13 of the sheath is provided with one or more tongues 14 spaced from the bottom 15 of the sheath and preferably formed as integral, cut-out parts of the portion 13, and the member 10 is provided with suitable apertures 16. The tongues enter the apertures or openings 16 of the member 10 and are bent over the edges of the apertures or openings at the opposite side of the member 10 from the sheath portion 13. This construction with the integral tongues extending over into the pocket, leaves no projecting parts on the rear side of the card or holder and effectively secures the sheath on the card or holder, a portion of the member 10 being securely gripped

between the bottom 15 of the sheath and the

tongues 14. The tongues and the bottom of the sheath oppose movements of the sheath relatively to the member 10 in opposite directions and the tongues by engagement with the side edges of the apertures in member 10 prevent detaching movements of the sheath relatively to member 10 transversely of that member.

Any suitable number of these tongues and openings in the card or holder may be provided and the tongues in addition to securing the sheath on the holder, assist in retaining the cards or label slips in the pocket, as is apparent from Fig. 3 of the drawings wherein there is illustrated a card inserted in the pocket, the tongues 14 frictionally engaging the cards and tending to prevent removal of the cards from the pocket. As illustrated, the tongues are preferably bent downwardly, thereby permitting relatively free insertion of the cards or the like, but, as heretofore stated, tending to prevent removal of the same.

As best illustrated in Fig. 4, if desired, the openings in the member 10 may be made of greater length than the width of the tongues, thus permitting a limited amount of lengthwise movement of the sheath relatively to the card or holder.

If desired, the sheath may be provided with a suitable projecting resilient part or parts adapted to assist in retaining a card or slip in the pocket, such as described and claimed in my application Ser. No. 606,444,

35 filed December 12, 1922, as for example, the inwardly extending rib 18 in the form illustrated. This rib 18 functions to frictionally retain a card or slip in the pocket and cooperates with the tongues 14 to hold the card 40 or slip in place, the rib engaging one side of the card and the turned-over tongues engaging the opposite side of the card.

Suitable provision may be made for closing the ends of the pocket. As illustrated in Fig. 1, this may be done by means of staples or the like 17, which staples in addition to closing the ends of the sheaths, may, if de-

sired, be attached to member 10, as shown.

In the claims the card or card holder is referred to generally as a holding member 50 for the purpose of holding or supporting the sheath or pocket.

I claim as my invention:

1. In an index device, a holding member, a sheath on an edge of said holding member, 55 said sheath having a portion forming a pocket for receiving an insert and a portion of less width than said pocket-forming portion, said holding member being provided with apertures, and parts on said last-named sheath portion projecting through said apertures and engaging an edge thereof, said parts being of less width than said edge whereby said sheath is secured on said holding member and a limited movement of said 60 sheath relatively to said holding member is permitted.

2. In an index device, a holding member, a sheath straddling an edge of said holding member, said sheath having at one side of 70 said holding member a pocket-forming portion and an attaching portion at the other side of said holding member, said attaching portion having integral parts extending through said holding member into said 75 pocket and gripping said holding member to retain said sheath on said holding member, and an offset portion on said pocket-forming portion projecting toward said holding member for frictionally engaging 80 an insert in said pocket.

3. In an index device, a holding member, a sheath on an edge of said holding member, 85 said sheath having a portion at one side of said holding member forming a pocket for receiving an insert, an attaching portion, a part on said attaching portion extending into said pocket for preventing unintentional removal of an insert from said pocket, and a projection on said pocket-forming portion 90 cooperating with said attaching portion part for retaining an insert in the pocket.

JAMES H. RAND, JR.
